UNITED STATES PATENT OFFICE

JOSEPH A. FIRSCHING, JR., OF ONEIDA, NEW YORK

UNDERGARMENT

Application filed November 1, 1929. Serial No. 404,084.

This invention relates to a new and improved under garment.

A great many individuals, either from necessity or for comfort, are obliged to wear 5 a suspensory bandage for the scrotum particularly when engaged in athletic activities.

When this is the case, it is necessary that they obtain some special device constructed for this particular use which is worn in addition to the under garment worn by the user. 10 This use of a special device is necessary because of the fact that all under garments known to the art are designed and made in such a way that they function merely as a 15 covering and provide no support for any part of the body.

The main object of my invention is to provide an under garment of such a design and shape that when in position on the wearer, 20 it will itself form a suspensory bandage so that the single garment will serve the purpose of the ordinary under garment and will also function as a suspensory, and the necessity of a special suspensory will be dispensed 25 with.

Other objects and advantages relate to the size, shape and arrangement of parts all as will more fully appear from the following description taken in connection with the accompanying drawings in which:—

Figure 1 is a front elevation of my garment in the open position.

Figure 2 is a rear elevation similar to Figure 1.

Figure 3 is a section on line 3—3 of Figure 1.

Figure 4 is a perspective front view of my garment with the parts in approximately the position they assume when in position on the user.

Figure 5 is a section on line 5—5 of Figure 4.

Figure 6 is a plan view of the piece of fabric which is used to form the left side of the garment.

Figure 7 is a plan view of the piece of fabric which is used to form the middle portion of the rear and a portion of the under part of the garment.

Figure 8 is a plan view, partially broken

away, of the piece of fabric which is used to form the right side of the garment.

Figure 9 is a plan view of the fabric used to form a portion of the front and a portion of the under part of the garment.

My garment may, of course, be made of any material or combination of materials appropriate for use as an undergarment, as for example, silk, rayon or any other fabric of proper weight and material.

Referring to Figures 6, 7, 8 and 9, the fabric to be used is cut to the shape there disclosed.

The left side portion 1 and the rear portion 2 are joined together as by sewing with the edge 3 of portion 1 joined to the edge 4 of portion 2. The upper end of portion 2 is provided with a slit 5 so that the material on the opposite sides of the slit 5 may be made to overly slightly to bring them into the position shown in dotted lines on Figure 7, such overlying portions being sewed together as shown at —a— on Figure 2, for the purpose of reinforcing that part of the garment.

The other edge 6 of portion 2 is in a similar manner secured to the edge 7 of the portion 8 shown in Figure 8.

The edge 9 of portion 10 is then secured in a similar manner to the edge 11 of portion 1.

A portion of the edge 12 of portion 10 is then secured to the edge 13 of portion 8, this last mentioned jointure being made only at the top and bottom of portions 8 and 10 leaving an opening 14 between such edges 12 and 13.

The part of portion 10 which is not secured to portion 8 is preferably re-inforced with a double strip of fabric 15 as shown on Figure 3 and the part of portion 8 which is not joined to portion 10 is similarly preferably re-inforced by a double strip of fabric 16 also shown on Figure 3.

The bottom edge 17 of portion 2 is then secured as by sewing to the bottom edge 18 of portion 10.

The lower right hand end 22 of portion 2 is then joined to the lower right hand end 23 of portion 10. The left lower end 24 is then joined to the left lower end 25 of portion 10.

An endless band of elastic 19 has its bot-

100

tom edge secured to the upper ends of portions 1, 2, 8 and 10, as by sewing as indicated at —b— on Figure 1, so that the same may, through its inherent resiliency, hold the garment securely in position on the wearer, the expansion and contraction of the elastic 19 being permitted due to the fact that the material of which the garment is made may be stretched to a considerable extent.

10 It will be noted that the bottom edge 17 of portion 2 has its central part of convex form and has its opposite ends of concave form and the bottom edge 18 of portion 10 is similarly formed.

13 It will also be noted that the length of the portion 2 from top to bottom is considerably greater than the length of portion 10 from the top to bottom.

With the garment in the open position with 20 its opposite sides stretched outwardly, it will assume the position shown in Figures 1 and 2 with the seam 20 which forms the joint between portions 2 and 10 a considerable distance above the bottom of the garment which 25 is due to the fact that the distance from the top of portion 10 to the seam 20 is less than the distance from the top of portion 2 to such seam 20.

When the opposite sides of the garment 30 are moved towards each other into the position which they will assume when the garment is in position on the user, the part of the garment formed by the portions 2 and 10 will be moved inwardly and downwardly 35 into the position shown in Figures 4 and 5 to form a pouch 21.

The distance from the top of portion 10 to the center point of pouch 21 being less than the distance from the top of portion 2 40 to such center point of pouch 21 it will cause the pouch 21 to be held in a position forward of the center point of the garment and in a position where it will form a suspensory bandage for the scrotum.

45 For the purpose of finishing the garment so that it will have an attractive appearance and give longer wear, I prefer to bind the bottom ends of the leg openings as indicated at —c— and —d—.

50 Although I have here shown a garment having an elastic means at its upper end for securing it in position on the wearer, it will be obvious that other means may be employed such as buttons and button holes if desired.

55 Although I have here shown a particular number of parts and a particular shape of the parts used, it will be understood that the number of parts and the shapes thereof may be varied to a considerable degree without 60 departing from the spirit of my invention, for although I have shown and described a specific structure and form of part as an exemplification of an embodiment of my invention, I do not desire to restrict myself to the 65 exact size, shape or arrangement of parts as

various changes may be made within the scope of the appended claims.

I claim:

1. In an undergarment, opposed side members, a triangular front member having one edge convex in the center and concave at each end and having its other two edges joined to the front edges of the side members, and a second triangular rear member having one edge convex in the center and concave at each end and having its other edges joined to the rear edges of the side members, said triangular members having their curved edges joined together, the first named triangular member being less in length than the second named triangular member. 75

2. In an undergarment, opposed side members, a triangular front member having its bottom edge convex in the center and concave at each end and having one of its other edges joined to one of the side members and having the other edge joined to the other side member at the top and at the bottom, and a second triangular rear member having its bottom edge convex in the center and concave at each end and having its other edges joined to the rear edges of the side member, said triangular members having their curved sides joined together, the first named triangular member being less in length than the second named triangular member. 85

In witness whereof I have hereunto set my hand this 14 day of October, 1929.

JOSEPH A. FIRSCHING, JR.
